UNITED STATES PATENT OFFICE.

ROBERT L. MYERS, OF BROOKLYN, NEW YORK, ASSIGNOR TO J. AND P. B. MYERS, OF NEW YORK, N. Y., A FIRM.

DESIGN FOR A PAPER BOX.

SPECIFICATION forming part of Design No. 35,944, dated June 10, 1902.

Application filed May 5, 1902. Serial No. 106,105. Term of patent 3½ years.

To all whom it may concern:

Be it known that I, ROBERT L. MYERS, a citizen of the United States, and a resident of Brooklyn, county of Kings, and State of New York, have invented a new and original Design for a Paper Box, of which the following is a specification, reference being had to the accompanying drawing, which represents a perspective view of a paper box showing my new design.

As shown in the drawing, the leading feature of my design consists of a paper box A, upon one side of which is represented a sleigh a, drawn by reindeers b. The sleigh contains

the conventional figure of Santa Claus c, carriage-robcs d, and a number of toys e. A house f is represented in front of the sleigh in perspective.

What I claim is—

The design for a paper box, substantially as herein shown and described.

Signed by me at New York city, New York, this 3d day of May, 1902.

ROBERT L. MYERS.
